NURSE'S CAP

Joseph C. Kail, Scarsdale, N.Y. (White Crown Company, 81 Warburton Ave., Yonkers, N.Y.)

Filed Sept. 16, 1965, Ser. No. 87,028

Term of patent 14 years

(Cl. D3—13)

FIG. 1 is a front perspective view of a nurse's cap, showing my new design;

FIG. 2 is a bottom plan view of said cap;

FIG. 3 is an enlarged fragmentary view thereof.

The cap is symmetrical and of uniform appearance around the side thereof. The crown of the cap is diaphanous.

I claim:

The ornamental design for a nurse's cap, substantially as shown and described.
